UNITED STATES PATENT OFFICE

HECTOR RABEZZANA, OF FLINT, MICHIGAN, ASSIGNOR TO A C SPARK PLUG COMPANY, OF FLINT, MICHIGAN, A COMPANY OF MICHIGAN

SPARK PLUG

Application filed December 7, 1928. Serial No. 324,509.

It is a general object of this invention to contribute to the efficiency, reliability, and durability of spark plugs; and this invention relates, so far as its immediate commercial use is concerned, exclusively to the interior insulation of spark plugs comprising mica "washers," or the like.

It being well known that internal combustion engines are liable to function unsatisfactorily when spark plugs and/or adjacent parts are unduly cold and also when said parts are excessively hot, and well known also that leakage and rapid deterioration may result from marked inequalities of temperature in the parts of spark plugs, it is an object of this invention to provide spark plug constructions which tend toward a prompt equalization of temperature throughout mica insulation, or the like, by a limited conduction of heat away from exposed surfaces thereof; and preferred embodiments of this invention also tend at all times to prevent such local overheating of spark plug parts as to involve danger of pre-
25 ignition or other detrimental effects.

Various features of the spark plugs disclosed being elsewhere described and claimed, the present application is directed more particularly, as indicated by the above title, to a novel use of so-called "sandwich" insulation,—this being produced by interposition of heat conductor elements between insulating elements and employed in assemblies disposed in the region of the spark gaps of the plugs referred to. The special type of insulation herein referred to may appear paradoxical, in that the sheets or washers of highly conductive metal, such as copper, are interposed between sheets or washers of an insulating material such as mica; but it should be understood that it is a primary object of this invention favorably to modify the head gradient within insulated assemblies of the general character referred to.

45 The edges of mica "washers" secured in proximity to spark gaps being unavoidably exposed to high temperature and high pressures, and the low thermal conductivity of such washers having been found to tend 50 toward leakage and avoidable deterioration,

this invention aims at what might be termed a compromise in regard to the local overheating problem,—by so proportioning and using interposed metallic "washers" as to obtain, while avoiding unduly close proximity between oppositely charged metallic parts, a satisfactory flow of heat into and through such insulating "washers." This is preferably done in such manner as to assure a satisfactory balance of tendencies, both during starting and during continued operation; and advantageous embodiments of this invention may comprise assemblies of the mentioned sandwich type insulation in connection with either an inner electrode or a 65 grounded electrode shell, or in connection with both.

Other objects of this invention, including various optional or alternative features of construction, may be best appreciated from the following descriptions of embodiments thereof, taken in connection with the appended claims and the accompanying drawings.

Figure 1 is a vertical or longitudinal sectional view through one simple and advantageous form of spark plug illustrating the present invention.

Figure 2 is a somewhat similar view, with some parts shown in elevation and some parts broken away, showing an alternative form.

Figure 3 is a view, corresponding to the lower portion of Figure 2 but showing an additional alternative form.

Reserving for final description that simple and advantageous form shown in Figure 1, attention may be first directed to those interior parts shown in Figure 2 as disposed within a special shell 10. In Figure 2, an inner and substantially central electrode 11, provided at its opposite ends with stop or head 12 and with an initially movable stop element in the form of a collapsed nut 13, is shown as provided not only with an exterior insulation assembly 14, retained by the nut 13 and a cooperating stop element in the form of a special bushing 15, but also with an interior insulation assembly 16,—the lat- 100

ter being of that "sandwich" type upon which protection is herein sought.

The bushing 15 being illustrated as of the so-called "rough-neck" type, a mica sleeve 5 or "cigarette" 17 and a protecting tube 18 are shown as disposed concentrically upon the electrode 11 and within said bushing in such manner that the inward collapse of weakened zones 19, 20 and 21, as effected 10 by a deformation of said tube, serves not only to retain the bushing 15 in such a position upon the electrode 11 as to hold the inner insulation assembly 16 under a desired compression, but also to obviate leakage longitudinally of said electrode. Either 15 the mentioned bushing and/or the shell 10 may be of any desired alternative type, so far as concerns the present invention; and, a gasket 22 being suitably inserted, the shell 20 10 is shown as having been also exposed to a thermoplastic collapse in an intermediate zone 23,—presumably after or in addition to an inward deformation of a retaining flange 24, adapted to engage a rounded surface 25, provided by the bushing 15.

In the form shown in Figure 2, so-called "sandwich" insulation being therein employed only in connection with the interior insulation assembly 16, separate sheaves 26, 30 27, 28, 29 and 30 of mica insulation are shown as separated by metallic washers 31, 32, 33 and 34,—the washer 34, if employed at all, being optionally of such interior diameter as to space the same from the electrode 11 and being optionally provided with a leak-preventing annular extension contacting with and/or gripped by the insulation sleeve 30. If desired, the washer 34 may be formed integral with the metallic element 40 of a copper-asbestos gasket 22; or it may be otherwise adapted to serve as a wedge-fitting and leak-preventing element contacting with a suitable surface provided within the lower or inner section 10' of the shell 10 or its equivalent; but it will be understood that, 45 as illustrated in the case of the metallic washers 31—32, the conductive elements carried by any inner electrode element will ordinarily be of such interior diameter or 50 diameters as to insure heat-conductive contact therewith; and an entire electrode spindle, comprising all the elements shown and mentioned as carried by the electrode 11, may ordinarily be assembled and thereafter 55 seated under pressure within any shell 10, in advance of the inward deformation of the flange 24 and by such a thermoplastic collapse of the weakened zone 23 as to assure a subsequent contraction of said shell and 60 the retention of all parts in their indicated relationships.

In Figure 3, a shell 10^a is shown as receiving an electrode 11^a which is provided with a head 12^a, a bushing 15^a being so inwardly 65 collapsed as radially to compress a "ciga-

rette" 17^a by the deformation of a protecting tube 18^a,—said deformation being effective to retain under a desired compression an inner insulation assembly 16^a; and the bushing 15^a and shell 10^a are shown as respectively provided with oppositely facing shoulders 35^a and 36^a adapted to cooperate in the retention of an auxiliary insulation assembly 37^a.

Either or both of the insulation assemblies 75 shown in Figure 3 may be of the "sandwich" type. The assembly 16^a is shown as including, in addition to interposed metallic washers 32^a and 33^a, corresponding in both interior and exterior diameter with the adjacent mica washers, a special washer 31^a, interiorly provided with a conductive flange which engages the electrode 11^a, and also with special washers 34^a and 38^a whose interior diameter so exceeds the diameter of the electrode 11^a as to obviate risk of electrical conduction thereto; and the washer 38^a is shown as provided with an exterior flange so interposed between the upper portions of the insulation assemblies 16^a and 37^a 80 as to assure a wedging and leak-preventing effect. In the case of the auxiliary insulation assembly 37^a, adapted not only to be radially wedged but to be held under axial compression in substantially the same manner as the gasket 22 of Figure 2, metallic washers 39^a, 40^a and 41^a are shown as corresponding in all horizontal dimensions with the adjacent mica washers; but, merely by way of 85 further illustrating possible special constructions that fall within the scope of the present invention, the washers 42^a and 43^a are shown not only as of greater interior diameter than the adjacent washers (this construction tending to obviate risk of an unintended sparking between washers employed in the insulation assembly 16^a and the washers 42^a, 43^a), but also with an interconnecting web of flange 44^a,—deemed especially effective, like the flange provided upon the washer 31^a, in assuring a desired conduction of heat from said washers to the adjacent electrode.

In that simple and advantageous embodiment shown in Figure 1, an electrode 11^b, provided with a stop in the form of a shouldered head 12^b, is shown as having collapsed thereon both a stop element in the form of a nut 13^b, of so-called "air craft" type, and also an intermediate retaining element or stop in the form of a bushing 15^b, an inner insulation assembly 16^b being interposed between the head 12^b and the bushing 15^b and an outer insulation assembly 14^b being interposed between said bushing and the nut 13^b, to complete a pre-formed inner electrode spindle secured within a shell 10^b. Said shell is shown as providing a shoulder or seat 36^b adapted to cooperate with an opposing face 35^b, provided by a sheaf of mica 130

insulation 26^b, included within the inner insulation assembly 16^b, in the retention of an auxiliary insulation assembly 37^b; and the latter may consist exclusively of mica sheaves 45^b, interposed between metallic washers 39^b, equal thereto in both interior and exterior diameter. In this embodiment of the present invention it will be understood that, all parts between the head 12^b and the nut 13^b being 5 preassembled under a suitable axial pressure (as by a thermoplastic collapse of the nut 13^b, substantially as indicated at 46^b), the auxiliary insulation assembly 37^b may be put and kept under a desired axial compression 10 incidentally to an inward deformation of the flange 34^b, or its equivalent (a gasket being shown as interposed at 22^b, between shoulders 47^b and 48^b, provided respectively on the shell 10^b and the bushing 15^b), and/or 15 by a thermoplastic collapse of a reduced or otherwise weakened zone 23^b of the shell 10^b, or its equivalent.

It will be appreciated that the comparatively simple construction last described involves the use of but one type of conductive washer; that the steps involved in its assembly are comparatively few and inexpensive; and this form is found highly satisfactory in practice,—a lateral spacing of the 20 collapsed zones 23 (or 23^b) from the bushing therein, when collapse is provided for, being advantageous as obviating any danger of damage to washers and/or gaskets comprised in any interior insulation assembly.

30 Although the foregoing description has included a plurality of embodiment of the present invention, it should be understood not only that various features thereof might be independently used, but also that numerous additional embodiments might easily be devised,—without involving the slightest departure from the spirit and scope of the present invention as the latter are indicated in the following claims.

45 I claim:

1. A spark plug comprising: an inner electrode element, provided with a head; a grounded electrode shell element surrounding said inner electrode element; and "sandwich type" insulation, comprising thermally conductive elements interposed between electrically non-conductive elements and so disposed between said electrode elements in the 50 region of said head as to augment the flow of heat from said region.

2. A spark plug as defined in claim 1 in which sandwich type insulation is carried by said inner electrode element and immediately above said head.

60 3. A spark plug as defined in claim 1 in which sandwich type insulation is carried opposite said head and by said shell element.

4. A spark plug as defined in claim 1 in which said inner electrode element is comprised in a spindle, some of said sandwich

type insulation being comprised in an auxiliary insulation assembly.

5. A spark plug as defined in claim 1 in which said inner electrode element is comprised in a spindle, some of said sandwich type insulation being comprised in an auxiliary insulation assembly which is held under compression through said spindle. 70

6. A spark plug as defined in claim 1 in which some of said thermally conductive elements are metallic washers interposed between mica washers and in heat-conductive contact with one of said electrode elements. 75

7. A spark plug as defined in claim 1 in which some of said thermally conductive elements are metallic washers interposed between mica washers and substantially equal thereto in both interior diameter and exterior diameter and in heat-conductive contact with one of said electrode elements. 80

8. A spark plug as defined in claim 1 in which some of said thermally conductive elements are opposite said head and so differ from adjacent non-conductive elements in diameter as to obviate sparking thereto. 85

9. A spark plug as defined in claim 1 in which some of said thermally conductive elements are immediately above said head and so contact with said inner electrode as to facilitate thermal conduction therethrough. 90

10. A spark plug as defined in claim 1 in which some of said thermally conductive elements so contact with said shell as to facilitate thermal conduction therethrough from said region. 95

11. A spark plug as defined in claim 1 in which some of said thermally conductive elements are provided with conductive flanges engaging an adjacent electrode element.

12. A spark plug as defined in claim 1 in which some of said thermally conductive elements are interconnected by thermally conductive webs. 105

13. For use in a spark plug, sandwich-type insulation comprising: thermally conductive elements interposed between electrically non-conductive elements, some of said thermally conductive elements being "washers" which differ in diameter from said electrically non-conductive elements in such manner as to facilitate thermal conduction therethrough and nevertheless to obviate electrical conduction therethrough. 110

In testimony whereof I affix my signature.
HECTOR RABEZZANA.
